UNITED STATES PATENT OFFICE.

ALFREDO LEBLANC, OF STAMFORD, CONNECTICUT.

GLOVE-FASTENER.

SPECIFICATION forming part of Letters Patent No. 749,618, dated January 12, 1904.

Application filed March 20, 1899. Serial No. 709,768. (No model.)

To all whom it may concern:

Be it known that I, ALFREDO LEBLANC, a citizen of the United States, residing at the city of Stamford, county of Fairfield, and State of Connecticut, have invented a new and useful Improvement in Glove-Fasteners, of which the following is a specification.

The present invention relates to glove-fas-
teners, and has for its object to provide a
glove-fastener member which shall be more
readily available for the purpose of orna-
mentation than those generally in use.

The object of the invention is attained by
making the upper member of a glove-fastener
in such manner that the locking portion is lo-
cated entirely upon the under side of the glove
material and practically does not project up
so as to cause an irregularity in the surface
of the glove material which presents a sub-
stantially flat surface upon the upper side.
Located upon the upper side of the glove ma-
terial is an operating-piece which is made in
any desirable shape, the function of this op-
erating-piece being to afford a thumb-piece
by which the locking portion of the fastener
on the under side of the glove may be locked
with and unlocked from a stud member.

Referring to the drawings, Figure 1 shows
a plan view of the female member embodying
my invention, the same being attached to a
piece of fabric, the securing or locking por-
tion being shown in dotted lines. Fig. 2 is a
section along the line 2 2 of Fig. 1, showing
the male member in engagement with the fe-
male member. Fig. 3 is a plan view of the
under side of the fastener member.

Referring to the drawings in detail, 1 indi-
cates the operating or thumb piece, which is
here shown in the form of a horseshoe. The
securing-piece is located upon the under side of
the glove material and consists of a simple shell
2, whose general outline is saucer shape, be-
ing provided with a concave or beveled lock-
ing portion 4, cut away at 3, so as to form a
locking-hook 5. As shown in the drawings,
the operating-piece and the locking portion 2
are secured together and to the glove material
by means of tongues 6, extending from the in-
ner edge of the portion 1 and passing through

suitable slits in the glove material and the shell 50
2 and being folded against the outside surface
of said shell 2, as clearly shown in Fig. 3. It
will be understood that the parts 1 and 2 may be
separately and independently connected to the
glove material in any well-known or conven- 55
ient manner. The stud or male member at-
tached to the other portion of the glove is in
engagement with the opposite member 2, the
head 7 taking over and being held by the hook
5. Said male member may be constructed in 60
any suitable manner and fastened to the glove
in any desired fashion, and further descrip-
tion thereof is not deemed necessary, since it
forms no part of the present invention. The
head 7 is prevented by the beveled portion 4 65
from pressing forcibly against the glove ma-
terial, and thus the formation of a protuber-
ance of the glove material is avoided.

It will be seen that by this invention the
widest possible latitude for purposes of orna- 70
mentation is given to that part of the glove-
fastener which is apparent to the eye when
the glove is worn, as said portion has for its
necessary function only to provide a thumb-
piece whereby the locking portion may be ac- 75
tuated. In my construction also it will be
seen that it is not necessary to cut out any
material portion of the glove material in order
to secure the locking member, and no locking-
dome is required, which permits of giving any 80
form of ornamentation or any shape to the
operating or thumb piece, and the designer
is not limited to stamping or otherwise rep-
resenting the desired ornamentation upon a
circular or other shaped disk, as is necessary 85
where a dome is required to lock the parts to-
gether and to cover mutilated parts of the
glove material.

I do not restrict my device to the specific
features described and shown, but believe that 90
I am entitled to such changes as come within
the spirit of the invention.

I claim—

In a glove-fastener, a female member com-
prising a shell made of a single integral piece 95
of metal fastened to the inside of the glove
material and having a concave locking por-
tion lying wholly below the glove material,

said locking portion being partially cut away to form a hook; a male member comprising a stud fastened to the opposite portion of the glove material and adapted to engage with the
5 said concave locking portion and said hook, the stud being held firmly in engagement with said female member but prevented by the same from forcibly engaging with the glove material; and an operating thumb-piece fastened to the outside of the glove material above

said female member for actuating the latter; substantially as described.

In witness whereof I have hereunto set my hand, in the presence of two subscribing witnesses, this 14th day of March, 1899.

ALFREDO LEBLANC.

In presence of—

IDA HOPKINSON,

SEABURY C. MASTICK.
